SHOPPING BAG

Harford K. Steen, Newburgh, N.Y., assignor, by mesne assignments, to Interstate Bag Company, Inc., a corporation of Virginia

Filed Aug. 6, 1957, Ser. No. 676,675

2 Claims. (Cl. 229—54)

This invention relates to paper shopping or carrying bags embodying the features of the bag disclosed in U.S. Patent No. 2,346,710. It is the primary object of the invention to provide a bag of the kind referred to with a liner composed of paper which is waxed or otherwise treated on one face for imparting desirable moisture and/or vapor barrier properties.

The bag of Patent No. 2,346,710 is a familiar article of commerce, having been produced in large quantity on high speed, continuously rotary bag making machinery. The bag itself includes a main body provided with an adhesively secured reinforcing strip which extends substantially all the way round the bag inside the mouth thereof. The bag further includes a pair of opposed twine handles which are secured inside the mouth of the bag and which protrude outward from between the bag body and the reinforcing strip, being adhesively secured both to the reinforced body and the reinforcing strip.

While the modification of the bag to provide a continuous moisture and/or vapor barrier is highly desirable, the provision of such a barrier is a matter of some difficulty. It is not feasible to employ as bag body material a web of paper which is waxed on one side because that would interfere with the securement of good adhesive union in connection with the bottoming, seaming, reinforcing and handle attaching operations. A coated lining is therefore required if the desired barrier is to be provided without impairing the normal functional characteristics of the unmodified bag.

The application of a liner to the bag presents a problem. In the manufacture of the unlined bag a difficulty was found to exist in connection with the severance of each blank length because of the previous attachment of the handles. Since the previously attached handles extended across the line of severance the problem was to sever the blank lengths from the web without severing the handles. In order that the severance of the handles may be avoided, the body web is pre-slit across the handle zones to form partial lines of severance before the handles are applied, and the severance is completed after the handles are applied without cutting into the handle zones. The coated liner web presents a like problem.

It is a feature of the invention that the liner web, before it is brought into meeting relation with the body web, is preliminarily slit across the handle zones and is adjusted, if necessary, into phase with the body web so that the slits of the liner web will be fed substantially into register with the slits of the body web after the reinforcement and the handles have been applied to the body web. With this arrangement the subsequent completion of the lining web severance may be effected concurrently with, and as an incident of, the subsequent completion of the body web severance. In other words, the travelling liner web is pre-slit and is then registered with the pre-slit body web, the bag manufacturing procedure being otherwise substantially in accordance with the standard procedure for an unlined bag of the kind referred to.

2

Other objects and advantages will hereinafter appear. In the drawing forming part of this specification—

Figure 1 is a perspective view of an illustrative bag embodying the present invention:

5 Figure 2 is a diagrammatic view in side elevation showing the preparation and assembly of the body and lining webs, the reinforcing strips and the handles, prior to final severance and bottoming.

Figure 3 is a perspective diagrammatic view showing 10 the steps successively performed by the mechanism of Figure 2;

Figure 4 is a fragmentary sectional view taken on the line 4—4 of Figure 3, looking in the direction of the arrows;

15 Figure 5 is a sectional view of the novel bag according to the invention, the section being taken on the line 5—5 of Figure 1, looking in the direction of the arrows;

Figure 6 is a fragmentary plan view on a larger scale 20 than Figure 3, showing details of a handle, the paste pattern, a reinforcing strip and the webs.

The diagrammatic showing of Figure 2 is generally like that of Figure 1 of Patent 1,799,072, save that modifications have been included for taking care of the bag lining.

25 Figure 2 is the bag body paper is fed from a reel 10 in the form of a continuous flat web 12 which may be strong kraft paper or any other suitable bag making paper. The web 12 is fed between a printing roller 14 and a bed roller 16, and thence between a cylinder 18 and a roller 20.

30 The cylinder 18 includes means of well understood construction, not shown in detail, for forming transverse slits 22 and longitudinal slits 24 at bag length intervals along the web 12. The cylinder 18 also includes means for applying reinforcing and lining attaching adhesive areas 26 and a lining attaching adhesive strip 28.

The roller 20 is also opposed by a roller 30. A reel 32 supplies a reinforcing web 34 to be severed into short lengths or patches 36 on the roller 30, the lengths being applied by the roller 30 at bag blank intervals to the 40 web 12.

45 Twine 38 is fed from reels 40 (one shown) to handle formers 42. The handle formers are timed in their operations to thrust the handles 44 simultaneously forward between the rollers 20 and 30 in such relation to the cutting off and the advancement of the reinforcing strip 36 that the strip is caused to overlie the attaching ends of the handles as seen in Figures 3 and 6.

50 Each gummed area 26 may be considered as composed of three zones: (a) the zone 26a which is covered by the reinforcing strip 36, (b) the zone 26b bounded on one side by the edge of strip 36 and on the other by the line of severance of which the slits 22 are to form parts, and (c) the zone 26c which lies to the right of the line slit in Figure 6. The adhesive of each zone 26a, serves to attach a strip 36 to one blank length of the body web

55 12 and also contributes to the attachment of the handles to the same blank length of the body web. The adhesive of each zone 26b extends around the inner face of the mouth portion of the blank length for attaching the upper margin of a liner blank length to the body web 12.

60 Ungummed areas 46 are provided in the zones 26c in line with each of the four handle legs to avoid smearing of the free portions of the handles with adhesives and to avoid undesired adhesion of the free portions of the handles to the lower or trailing end of the preceding blank lengths which they overlap.

65 Spots of paste (not shown) are applied to the handle engaging areas of the strip 36 prior to association of the handles with the strip. These paste spots cause the handles to be adhered to the strip 36, so that the strip serves as a supplementary connecting means between the handles and the body web 12.

With the slits 22 and 24 formed, the paste applied to the areas 26 and 28, and the patches 36 and the handles 44 applied, the web 12 is ready to have a coated lining web 48 adhered to it. The web 48, which is of substantially the same width as the web 12, is supplied from a reel 50. The web 48 has slits 52 and 54 (corresponding to the slits 22 and 24 of the web 12) formed in it by a cutter 56 which is composed of a knife carrying roller 58 and a bed roller 60. The slits 52 and 54 are designed to register exactly with the slits 22 and 24, respectively, when the webs 12 and 48 are brought together and combined with one another. Lateral registration presents no difficulty but it is important that the web 48 be adjusted into phase with the web 12, if adjustment should prove to be necessary.

After leaving the cutter 56, therefore, the web 48 is caused to pass a phase adjusting device 62 which comprises fixed guided rollers 64 and 66 and an adjustable intervening roller 68. If no adjustment is required the roller 68 is set in an inactive position such as the dotted line position designated 68a, to permit the web 48 to travel in a straight line between the rollers 64 and 60. The roller 68, may, however, be adjusted to increase to any desired extent the length of the web patch between the rollers 64 and 60, for example, to a position like that in which it is shown in full lines in Figure 2. The roller 68 can be readjusted with the machine in operation, thereby to bring about exact phase correspondence under visual control.

The web 48 is fed onto the web 12 at a combining roller 70. Although the webs 12 and 48, as noted, are of substantially the same width, they are not brought together in lateral registration. On the contrary, one margin 48a of the web 48 is caused partially to overlap the adhesive strip 28 so that a substantial margin 12a of the web 12 is left exposed, while the opposite margin 48b of the web 48 is caused to extend beyond the corresponding margin 12b of the web 12. The superposition of the webs causes the web 48 to be united with the web 12 in the areas of the stripe 28 and the zones 26b and 26c. The reinforcing strips 36 are made short enough and are appropriately placed to leave the stripe 28 continuously clear for contact with the web 48. Each strip 36 is located about a half inch below the line of blank severance in order to leave the paste zone 26a free for contact with the web 48.

After the roller 70 is passed, webs 12 and 48 are advanced in unison around a guide roller 72 and thence to a gummer 74. The gummer, as shown, comprises an adhesive applying roller 76 and a bed roller 78. The gummer 74 applies a stripe 80 of adhesive to the exposed margin 12a of the lining face of the web 12.

After passing the gummer 74 the composite web is fed through tubing mechanism of well known construction. The result of the tubing is illustrated in Figure 5. The margin 12b of the web 12 is caused to bear against the adhesive stripe 80 which has been applied to the margin 12a of the web 12. At the same time the margin 48b of the web 48 is caused to overlap the margin 48a of the web 48 and to bear in part against that portion of the adhesive stripe 28 which has been left exposed by the margin 48a.

The finished bag 82 (Figure 1) is bottomed in conventional manner, successive blank lengths being separated along partial lines of severance which coincide with,

and complement the slits 22 and 52. As will now be apparent, the novel bag comprises a body composed of the web 12 which is reinforced for a considerable width substantially all the way around the mouth of the bag by a reinforcing strip 36, is provided with a pair of registering handles 44 which protrude outward from within the mouth of the bag, and includes a complete liner composed of the web 48 which is desirably coated on the inner face with a suitable water and/or vapor repellent material such as wax.

While certain preferred embodiments of the invention have been illustrated and described in detail, it is to be understood that changes may be made therein and the invention embodied in other structures. It is not, therefore, the intention to limit the patent to the specific construction illustrated, but to cover the invention broadly in whatever form its principles may be utilized.

I claim:

1. A carrying bag comprising, in combination, a paper body member having a mouth, substantially registering handles secured to the bag mouth and protruding outward beyond the mouth, a reinforcing strip disposed to extend substantially all the way round the bag within the mouth thereof, said strip serving also to assist in securing the handles to the bag, and a complete liner within the bag which is substantially coextensive with the bag body member and which forms an uninterrupted inner bag wall, the liner being made unitary with the bag body member by being directly and continuously, adhesively united to the bag body along all four of the liner margins, and the reinforcing strip being spaced inward a short distance from the mouth of the body to expose an upper marginal portion of the body, the adhesive union of the upper margin of the liner with the body being effected along the upper marginal portion of the body which is exposed above the reinforcing strip, the material of the liner being interfolded and united with the material of the body member in the bottom area.
2. A carrying bag comprising, in combination, a paper body having a mouth, substantially registering handles secured in the body mouth and protruding outward beyond the mouth, a reinforcing strip disposed to extend substantially all the way around the bag within the mouth thereof but located to leave clear a margin of the body of substantial width, said strip serving also to assist in securing the handles to the inner faces of the body walls, and a complete, water impervious, tubed liner consisting of a sheet having a water resistant coating on its inner face, which sheet is substantially coextensive with the body, is adhered to the inner face of the body completely around the mouth of the body and along a zone which extends the full length of the body, and is interfolded and united with the material of the body in the bottom area.
